(57) **CLAIM**

I claim the ornamental design for a set of three goatee templates, as shown and described.

DESCRIPTION

FIG. 1 is a front elevation view of the first goatee template of the set of three goatee templates;

FIG. 2 is a perspective view thereof;

FIG. 3 is a front elevation view thereof;

FIG. 4 is a rear elevation view thereof;

FIG. 5 is a left side elevation view thereof;

FIG. 6 is a top plan view thereof;

FIG. 7 is a bottom plan view thereof;

FIG. 8 is a front elevation view of the second goatee template of the set of three goatee templates;

FIG. 9 is a perspective view thereof;

FIG. 10 is a front elevation view thereof;

FIG. 11 is a rear elevation view thereof;

FIG. 12 is a left side elevation view thereof;

FIG. 13 is a top plan view thereof;

FIG. 14 is a bottom plan view thereof;

FIG. 15 is a front elevation view of the third goatee template of the set of three goatee templates;

FIG. 16 is a perspective view thereof;

FIG. 17 is a front elevation view thereof;

FIG. 18 is a rear elevation view thereof;

FIG. 19 is a left side elevation view thereof;

FIG. 20 is a top plan view thereof; and,

FIG. 21 is a bottom plan view thereof.

The broken lines illustrate the environment of the set of three goatee templates and form no part of the claimed design.

The three goatee templates are shown separately for convenience of illustration.
